UNITED STATES PATENT OFFICE.

CEZAIRE JOLY, OF SALEM, MASSACHUSETTS.

RAIL-JOINT.

1,190,907.

Specification of Letters Patent. Patented July 11, 1916.

Application filed December 21, 1915. Serial No. 68,040.

To all whom it may concern:

Be it known that I, CEZAIRE JOLY, a citizen of the Dominion of Canada, residing at Salem, in the county of Essex and State of Massachusetts, have invented certain new and useful Improvements in Rail-Joints, of which the following is a specification.

The present invention appertains to improvements in rail joints, with the object in view of providing a simple article capable of being cheaply manufactured and readily applicable in position connecting two rail ends together in such a manner as to prevent the said rails from creeping or yielding under pressure of the rolling stock, such yielding action giving rise to the rounding of the ends of the rails and the imparting of undesired vibration to trains passing thereover.

20 The invention consists of a chair to receive the rails, provided with key seats, keys for distributing the pressure with respect to the chair having interlocking connection therewith to prevent displacement of the rails, the keys providing a water-tight joint, and means clamping the keys in and preventing displacement thereof from the chair.

The above and such other objects as may hereinafter appear are attained by the novel 30 construction, combination and arrangement of parts to be hereinafter specifically described and claimed.

Reference will now be had to the accompanying drawings forming a part of the 35 specification, wherein:

Figure 1 is a perspective view of the embodiment of my invention. Fig. 2 is a top plan view. Fig. 3 is an end elevation, parts being broken away to show more clearly the 40 details of construction. Fig. 4 is a horizontal sectional view taken about on the plane indicated by the line 4—4 of Fig. 1; and Fig. 5 is a transverse sectional view taken about on the line 5—5 of Fig. 4. Fig. 45 6 is a perspective view of a rail engaging member or key used in this device.

Throughout the following detail description, and on the several figures of the drawings, similar parts are referred to by like 50 reference characters.

Referring to the drawings, this device comprises the chair 1 upon which the ends of the rails 2—2 are seated, the base portion of the chair being provided with one or 55 more vertical projections or bosses 3 with which the bases of the rails coact, said rail

bases being provided with cut away portions in which the projections 3 are received. These projections are designed to prevent tendency of creeping of the rails as will be 60 obvious to those skilled in the art to which this invention refers. The base of the chair 1 is provided with lateral notches 4 with which spikes are adapted to engage to hold the chair in place upon the railway ties. 65 The chair is provided at each side with a lateral wall 5 extending vertically in spaced relation to the web of the rail, these walls forming seats to receive rail engaging members hereinafter more particularly described. 70 At the base of each wall in the inner face thereof is provided a longitudinally extending slot or groove 6 disposed substantially on a level with the upper face of the base of the rails arranged in the chair. 75

In each of the seats thus provided is introduced a heavy key on rail engaging member 7, most clearly shown in Fig. 6 of the drawing. The key 7 is of sufficient length to extend a short distance beyond the meeting ends of the rails 2, 2 and is interposed, of course, between said rails and the lateral wall 5 at the respective sides of the chair 1. Upon the inner side, the key is provided with an upper shoulder 8 which engages beneath the ball portion of the rails, and a lower shoulder 9 which engages with the base of the rails, while at the opposite side each key is formed with an upper flange 10 which overhangs the chair wall 5, and a 80 lower laterally projecting wedge flange 11 which is received in the groove 6 in this wall. It will be obvious that the overhanging flange 10 not only prevents access of 85 rain or foreign matter into the chair seat but by reason of its engagement with the chair wall the pressure on said chair due to traveling of trains over the rails is distributed between the base of the chair and its lateral wall. Owing to the substantial bearing of the ends of the rail upon the chair 90 through the instrumentality of the keys the ends of the rails are prevented from working upward and downward resulting in the rounding of the ends which causes the deleterious vibration or pounding action commonly inherent in the use of the usual forms 95 of rail connections. It will be noted that at one end each key 7 is formed with a lateral projection or head 12 which facilitates the 100 removal of the key from its seat in that the workman is enabled to hammer against this 105

110

projection to cause longitudinal displacement of the key. From the end of the key having the head or lateral projection 12, the flange 11 tapers in a transverse direction 5 with respect to the key and this tapering form provides the wedging function which interlocks the key in position.

The chair 1 at substantially its central portion is enlarged transversely as at 13, 10 said enlarged portion having a transverse passage or opening to receive clamping means for holding the key members in place in the chair. The clamping means just mentioned comprises a shank 14 which is inserted 15 in the opening of the enlarged portion 13, said shank being upturned at one end to form a hook 15, the extremity of which passes through an opening in the side wall 5 at one side of the chair and into engagement with the key 7 at this side. To insure positive interlocking action with respect to the key, the latter is preferably provided with one or more shallow recesses 16 to receive the extremity of the hook. The shank 25 14 is square in cross section and carries at its other end an adjustable arm 17 mounted on the square portion, this arm corresponding in shape substantially to the hook 15 and engaging the key arranged at the opposite side 30 of the rails in the same manner as the hook co-operates with the key first mentioned. The arm 17 is adjustable by means of the nut 18 having threaded connection with the end of the shank 14. It will be apparent that 35 the respective keys 7 are positioned in the seats of the chair by introducing them in opposite directions between the walls 5 and the rail ends and these keys will move into their normal engaging position substantially 40 freely though the wedge flange becomes effective just before the recesses 16 of said keys registers with the openings in the side wall through which the hook 15 and the arm 17 extend. By clamping the keys tightly in 45 the seats in the manner hereinbefore clearly set forth, a rigid and substantial connecting means is provided for rails and without the utilization of bolts which are generally provided for fishplates or angle bars of the 50 conventional type. The connection of rails by means of my invention may be quickly accomplished.

Having thus described my invention what I claim as new is:

55 1. A rail joint device of the class described comprising a chair having a seat arranged at each side of the rails, rail engaging members disposed in said seats, means for holding said members from displacement comprising a transversely arranged

clamp extending beneath the rail and having one end coacting with the rail engaging member at one side of the rails, and adjustable means carried by its other end engaging the opposite rail engaging member. 65

2. A rail joint device of the class described comprising a chair having a seat arranged at each side of the rails, rail engaging members disposed in said seats, means for holding said members from displacement comprising a transversely arranged clamp interlocked with the chair and having a hooked terminal at one end engaging the rail engaging member at one side of the rails, and a clamping arm adjustably carried by the other end for engaging the rail engaging member at the opposite side of the rails. 75

3. A rail joint device of the class described comprising a chair having a lateral wall 80 forming a key receiving seat, a key disposed in said seat and engaging the rails, the chair aforesaid having a transverse opening, and a clamping member arranged in the transverse opening and having one end upturned 85 to interlock with the lateral wall aforesaid, the end of said member engaging the key at the corresponding side of the rails and adjusting means on the other end of said clamping member for clamping the key 90 against displacement from its seat.

4. A rail joint device of the class described comprising a chair, a key member arranged intermediate the chair and the rail seated therein, a wedge flange on said key interlocking with the chair for preventing displacement of the key therefrom, and a clamping member extending transversely of the chair and co-operating with the key member to hold it in wedging position, the chair 95 aforesaid being formed with an enlarged portion having an opening therethrough to receive the transversely clamping member. 100

5. A rail joint device of the class described comprising a chair provided with 105 lateral seats, rail engaging members disposed in said seats, interlocking means intermediate the rail engaging members and the chair for preventing vertical displacement of the engaging members, and clamping means common to said rail engaging members and arranged transversely of the chair for engagement with said members to prevent longitudinal displacement of said members from the seats aforesaid. 110

In testimony whereof I affix my signature.

CEZAIRO ^{his} X JOLY.
